BLADE FOR WIRE STRIPPING TOOL

Walter J. Maytham, Los Altos, Calif., assignor to Speed Systems, Inc., Los Altos, Calif.

Filed July 2, 1971, Ser. No. 159,583

Term of patent 14 years

Int. Cl. D8—99; D15—99
U.S. Cl. D8—98

FIG. 6.

FIG. 1.

FIG. 5.

FIG. 2.

FIG. 3.

FIG. 4.

FIG. 1 is a perspective of a blade for a wire stripping tool embodying the new design;

FIG. 2 is a top plan of the blade;

FIG. 3 is a front elevation of the blade;

FIG. 4 is a bottom plan of the blade; and

FIGS. 5 and 6 are end elevations of the blade.

I claim:

The ornamental design for a blade for wire stripping tool, substantially as shown.
